DESIGN FOR A BUCKLE

Julius S. Tenney, New York, N. Y.

Application October 21, 1935, Serial No. 59,151

Term of patent 3½ years

To all whom it may concern:

Be it known that I, Julius S. Tenney, a citizen of the United States, residing in the county, city, and State of New York, have invented a new, original, and ornamental Design for Buckles, of which the following is a specification, reference being had to the accompanying drawing, forming part thereof.

Fig. 1 is a plan view of a buckle showing my new design, and

Fig. 2 is an edge view thereof.

Fig. 3 is a back view of the buckle shown in Fig. 1.

I claim:

The ornamental design for a buckle, substantially as shown and described.

JULIUS S. TENNEY.
